UNITED STATES PATENT OFFICE.

HERBERT ABRAHAM, OF NEW YORK, N. Y., ASSIGNOR TO THE RUBEROID COMPANY,
A CORPORATION OF NEW JERSEY.

DESIGN FOR A ROOF.

Application filed October 1, 1921. Serial No. 504,775. Term of patent 14 years.

To all whom it may concern:

Be it known that I, HERBERT ABRAHAM, a citizen of the United States, residing at the city, county, and State of New York, have invented a new, original, and ornamental Design for a Roof, of which the following is a specification, reference being had to the accompanying drawing, forming part thereof.

The drawing represents a plan view of an indeterminate portion of a roof, showing my new and ornamental design.

I claim:

The ornamental design for a roof substantially as shown.

HERBERT ABRAHAM.
